(57) **CLAIM**

The ornamental design for a boba tea plush doll, as shown and described.

DESCRIPTION

FIG. 1 is a top front perspective view of a boba tea plush doll showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top rear perspective exploded view thereof, with a zipper in an open position and boba pearls removed.

The broken lines shown in the drawings depict portions of the article that form no part of the claimed design. The broken lines shown in FIG. 8 represent a zipper which forms no part of the claimed design.

1 Claim, 5 Drawing Sheets
